UNITED STATES PATENT OFFICE.

FRANCIS SAUVAIRE, OF DALY CITY, CALIFORNIA.

HEATER.

Application filed January 31, 1928. Serial No. 250,836.

My invention relates to improvements in the construction and arrangement of air heaters wherein a current of air is forced through an air chamber heated by a burner, and delivered in a heated condition through a delivery connection to an outside point.

The primary object is to provide a heater of improved and simplified construction.

Another object is to provide an improved heater wherein a relatively large volume of air may be heated with a very small consumption of fuel.

A further object is to provide, as a new article of manufacture, an improved construction which will facilitate the construction and assembly of the heater and provide an economical and efficient heater.

A still further object is to provide an improved device wherein inlet and delivery connections are arranged to seal the passages between the inner and outer shells of the heater and to aline and retain said passages in proper relation.

My invention consists of the improved details of construction and arrangement disclosed in the drawings forming a part of the present application wherein like characters of reference are used to designate similar parts throughout the specification and drawings and in which—

Fig. 1 is a vertical mid-section of my improved heater construction;

Fig. 2 is a plan view of the heater; and Fig. 3 is a transverse horizontal section.

Referring to the drawings, my improved construction consists of an outer shell, designated in general by the numeral 1, provided with supporting legs 2 formed integrally therewith at the bottom thereof and provided with an outwardly extending shelf 3 adjacent the bottom of the shell. The shell 1 is preferably cast in one piece from suitable metal.

An air inlet opening 4 is formed in the wall of the shell near the bottom thereof and an air outlet opening 6 is formed in the shell near the top thereof, preferably directly above the inlet opening 4.

An inner shell consisting of spaced double walls 7 and 7' is mounted within the outer shell 1. The inner shell is supported by means of a flange 8 arranged at the top of the inner shell and provided with a shoulder 9 arranged to seat around the top of the outer shell 1. The inner wall 7 forms a vertically disposed central vent passage 5

open at top and bottom. The wall 7' is spaced from the wall 7 to form an air chamber 11 closed at top and bottom within the inner shell around the vent passage said wall 7' being also spaced from the shell 1 to form a heat chamber 10 between the inner and outer shells. Inlet and outlet passages 12 and 13 respectively, are formed upon the lower and upper ends of the inner shell to extend across the heat passage and register with the inlet and outlet openings 4 and 6. The inner shell is preferably cast in one piece.

An inlet connection 14 extends through the inlet opening 4 into the inlet passage 12, and an outlet connection 15 extends through the outlet opening 6 into the outlet passage 13. The connections 14 and 15 fit closely within the registering openings and passages to seal the passage therethrough and to hold the passage portions of the inner shell in proper registering relation to the corresponding openings in the outer shell.

A suitable fan 16 is mounted upon the shelf 3 and arranged to force a current of air through the inlet connection 14 into the air chamber 11, said current moving upwardly through the air chamber to be delivered through the outlet connection 15 through which it is conducted and delivered at a desired point.

A suitable gas burner 17 is mounted within the bottom of the shell 1 adjacent the bottom of the heating chamber 10, said burner being mounted in any suitable manner and supplied with fuel from a suitable source through a supply connection 18, the supply of fuel being controlled in the well known manner. An opening 19 is formed in the shell 1 near the burner 17 to admit air to support combustion of the fuel.

In operation, the heater, constructed and assembled as shown and described, is heated by the burner 17. Air forced through the chamber 11 is heated by contact and radiation from the walls 7 and 7' and is delivered in a heated condition through the delivery member 15, said heated air serving to heat a compartment to which it is delivered in the well known manner. The heat chamber 10, being open only at the bottom, does not permit a circulation of air and as a result, the air therein and the walls of the inner shell become heated to a relatively high temperature at which they are maintained by a very small burner 17. The air circulating

through the chamber 11 absorbs heat which is carried through the outlet connection to a point relatively remote from the heater if desired.

5. The structure described and illustrated is of particular advantage because of the simplicity and economy of construction. The outer shell is cast as one member with the legs 2 and shelf 3 formed integral therewith. 10. The inner shell is also an integral member having the supporting flange 8 and the inlet and outlet passages 12 and 13 cast integrally therewith. When assembled, the inner shell is supported in proper relation and seals the 15. top of the outer shell, and when the inlet and outlet connections 14 and 15 are applied, the shells are effectively secured together and the juncture between the passages and the openings in the outer shell effectively sealed. As a new article of manufacture, this improved structure affords a simplicity and economy in manufacture and installation constituting a material advance in the art.

20. Having thus described my invention what I claim as new and desire to secure by Letters Patent is—

1. As an article of manufacture, a heater comprising an outer shell having air inlet 25 and outlet openings; a double walled inner shell mounted within the outer shell and forming a central vent passage and an air chamber surrounding the vent passage; air inlet and outlet passages communicating 30 with the air chamber and arranged to register with the air inlet and outlet openings of the outer shell; air inlet and outlet connections extending through the inlet and outlet openings into the corresponding passages and arranged to seal and retain said 35 passages in communicating relation with said openings; a burner mounted within the outer shell to heat the inner shell; and means for forcing a current of air through 40 the air chamber of the inner shell whereby said air may be heated for delivery through the delivery connection.

2. As an article of manufacture, a heater comprising an outer shell having air inlet 45 and outlet openings and provided with supporting legs formed integral therewith; a double walled inner shell mounted within the outer shell and forming a central vent passage and an air chamber surrounding the 50 vent passage; air inlet and outlet passages opening into the air chamber and arranged to register with the air inlet and outlet openings of the outer shell; air inlet and delivery 55 connections extending through the inlet and outlet openings into the corresponding passages and arranged to seal and retain said 60 passages in communicating relation with said openings; a burner mounted within the outer shell to heat the inner shell; a shelf arranged adjacent the bottom of the outer shell; and a fan mounted upon said shelf and arranged to direct a current of air through the air chamber to be heated for delivery through the 65 delivery connection.

3. As an article of manufacture, a heater comprising an outer shell having air inlet 70 and outlet openings; a double walled inner shell mounted within the outer shell and forming a central vent passage and an air chamber surrounding the vent passage, said air chamber being closed at top and bottom; a flange carried by the inner shell and arranged to engage the upper edge of the outer shell to close the top of said outer shell and support the inner shell therein; air 75 inlet and outlet passages connected to the inner shell and communicating with the air chamber therein, said passages being arranged to register with the inlet and outlet openings respectively of the outer shell; air inlet and delivery connections extending 80 through the inlet and outlet openings into the corresponding passages and arranged to seal and retain said passages in communicating relation with said openings; a burner mounted within the outer shell to heat the inner shell; and means for forcing a current of air through the air chamber to be heated for delivery through the delivery connection.

4. As an article of manufacture, a heater comprising an outer shell having air inlet 85 and outlet openings; a double walled inner shell mounted within the outer shell and forming a central vent passage and an air chamber surrounding the vent passage, said air chamber being closed at the top and bottom; a flange carried by the inner shell and arranged to engage the upper edge of the outer shell to close the top of said outer shell and support the inner shell therein with the walls of said inner shell in spaced relation to the wall of the outer shell to form a heat passage therebetween; air inlet and outlet passages carried 90 by the inner shell and arranged to extend across the heat passage and to register with the inlet and outlet openings of the outer shell; air inlet and delivery connections extending through the inlet and outlet openings into the corresponding passages and arranged to seal and retain said 95 passages in communicating relation with said openings; a burner mounted within the outer shell to heat the inner shell; a shelf arranged adjacent the bottom of the outer shell; and a fan mounted upon said shelf and arranged to direct a current of air through the air chamber to be heated for delivery through the delivery connection.

5. As an article of manufacture, a heater comprising an outer casing forming a shell having air inlet and outlet openings adjacent the top and bottom respectively and provided with supporting legs and an outward- 100

ly extending shelf cast integrally with the shell; an inner casing consisting of a double walled shell forming a central vent passage and an air chamber surrounding the vent passage, said vent passage being open at top and bottom and the air chamber being closed at top and bottom; a flange cast integrally with the inner shell and arranged to seat upon the upper edge of the outer shell to close the top thereof and to support the inner shell with its walls in spaced relation to the outer shell to form a heat passage therebetween; air inlet and outlet passages cast integrally with the inner shell and arranged to extend across the heat pas-

sage into registering relation with the openings in the outer shell; air inlet and delivery connections extending through the inlet and outlet openings into the corresponding passages and arranged to seal and retain said 20 passages in communication with the openings; a burner mounted within the outer shell; and a fan mounted upon the shelf and arranged to direct a current of air through the air chamber to be heated for delivery 25 through the delivery connection.

In witness whereof, I hereunto set my signature.

FRANCIS SAUVAIRE.
